UNITED STATES PATENT OFFICE.

HOWARD G. MEAD, OF ST. LOUIS, MISSOURI, ASSIGNOR TO WILLIAM P. HEALY, OF CHICAGO, ILLINOIS.

WIRE-BOUND-BOX-BLANK MACHINE.

1,167,914.

Specification of Letters Patent.

Patented Jan. 11, 1916.

Application filed September 14, 1911. Serial No. 649,377.

To all whom it may concern:

Be it known that I, HOWARD G. MEAD, a citizen of the United States of America, and resident of the city of St. Louis, Missouri, have invented a certain new and useful Improvement in Wire-Bound-Box-Blank Machines, of which the following is a specification.

My invention relates to wire-bound box blank machinery of the kind in which adjustable spacing blocks are employed. For example, in Patent Number 864,955, an endless traveling work-holder is provided for holding the cleats and sheets of veneer, and for passing the same below the staplers. This traveling work-holder is provided with adjustable blocks for spacing the cleats apart endwise. It is the adjustability of these blocks to which my invention more particularly relates.

The object of my invention is to provide an adjustable spacing block which can be adjusted readily by hand and without the use of tools, whereby a machine of this kind may be changed very quickly for cleats of different lengths, thus saving time and labor in the manufacture of boxes of this character, as will hereinafter more fully appear.

To these and other useful ends, my invention consists in matters hereinafter described and claimed.

In the accompanying drawings—Figure 1 is a side elevation of a wire-bound box blank machine having spacing blocks embodying the principles of my invention. Fig. 2 is a perspective, on a larger scale, of a portion of one of the carrier chains of the said machine, showing one of my improved adjustable spacing blocks in place thereon. Fig. 3 is a plan of the said spacing block, on a still larger scale, showing a portion of said chain. Fig. 4 is a transverse section of the cam lever on line 4—4 in Fig. 3.

As thus illustrated, the machine shown in Fig. 1 is of the well known kind in which the blanks are carried on endless traveling chains A. Each chain is composed of suitable links having inner side pieces a provided externally with longitudinal grooves a' . The said chains are constructed and operated in any suitable, known or approved manner. The spacing blocks B on said chains are made to straddle the plates or inner side pieces a , and are adapted to space the cleats apart endwise in the usual and

well known manner. Each block, however, in accordance with my invention, is provided with a cam b mounted in a recess b' in the inner end of the block. The said cam is held in place by a vertical pivot b^2 that is removable from the bottom of the block, and that is preferably held in place by upsetting the metal of the block around the edge of the hole in which the pin is inserted, whereby nothing projects below the lower surface of the block. This pin or pivot can be easily removed, when it is necessary to remove the cam, by simply pressing the metal back from the lower end of the pin, in any suitable manner. The said cams have handles or levers b^3 that swing in horizontal planes, and that are curved to lie close to the chains to prevent them from catching on the wires, or any other portions of the machine. It will be understood that the handles b^3 on the blocks of one chain point rearward, while those of the other chain point forward, whereby the blocks are all alike. The cams b engage in the grooves a' of the chains, and when the levers b^3 are in the position shown in Fig. 3, the blocks B are locked in place. When it is desired to change the distance between said spacing blocks, in order to change the size of the box blank, as by using longer or shorter cleats, this is accomplished by simply pulling out the levers b^3 , and then, after the blocks are properly positioned, pushing the said levers back toward the sides of the chains. This operates the cams, to first release and then secure the blocks in place, and is all accomplished without the use of tools and in a comparatively short space of time. In this way the machine is quickly changed for cleats of different lengths, and the change each time requires less time and labor than heretofore. Thus the efficiency of the machine is materially increased.

What I claim as my invention is:

1. A machine for making wire-bound box blanks, adapted for use with cleats of different lengths, comprising blocks for spacing the cleats of the blank apart endwise, a chain, means for producing a step by step movement of the chain and blocks, and cams having handles for adjustably securing the blocks to said chain, and carried by portions of said blocks which are disposed at one side of the path of travel of the cleats.

2. A machine for making wire-bound box

- 2
- blanks, adapted for use with cleats of different lengths, comprising blocks for spacing the cleats of the blanks apart endwise, a chain, means for producing a step by step movement of the chain and blocks, levers pivoted on said blocks, the axes of said levers extending in a vertical plane at one side of said chain, and means operated by said levers for fixing the blocks to the chain, and carried by portions of said blocks which are disposed at one side of the path of travel of the cleats, said chain having means for insuring the correct position of the blocks thereon.
3. A machine for making wire-bound box blanks, adapted for use with cleats of different lengths, comprising blocks for spacing the cleats of the blanks apart endwise, a chain, means for producing a step by step movement of the chain and blocks, and means pivoted on the blocks for fixing the latter on the chain, and carried by portions of said blocks which are disposed at one side of the path of travel of the cleats, the axes of said means extending in a common vertical plane at one side of said chain, said chain having means for insuring the correct position of the blocks thereon.
4. A machine for making wire-bound box blanks, adapted for use with cleats of different lengths, comprising blocks for spacing the cleats of the blanks apart endwise, a chain, means for producing a step by step movement of the chain and blocks, and lever actuated cam mechanism for securing the blocks on said chain, and carried by portions of said blocks which are disposed at one side of the path of travel of the cleats, whereby the distance between said blocks may be changed at will, said chain having means for insuring the correct position of the blocks thereon.
5. A machine for making wire-bound box blanks, comprising blocks for spacing the cleats of the blanks apart endwise, a chain, and cams for adjustably securing the blocks to said chain, said chain having a side wall, and each block being split to straddle said wall, said wall and said cams coöperating to hold the blocks against upward movement.
6. A machine for making wire-bound box blanks, comprising blocks for spacing the cleats of the blanks apart endwise, a chain, levers pivoted on said blocks, and means operated by said levers for fixing the blocks on the chain, said chain having a side wall, and each block being split to straddle said wall, said wall and said means coöperating to hold the blocks against upward movement.
7. A machine for making wire-bound box blanks, comprising blocks for spacing the cleats of the blanks apart endwise, a chain, and means pivoted on the blocks for fixing the latter on the chain, said chain having a side wall, and each block being split to straddle said wall, said wall and said means coöperating to hold the blocks against upward movement.
8. A machine for making wire-bound box blanks, comprising blocks for spacing the cleats of the blanks apart endwise, a chain, and lever-actuated cam mechanism for securing the blocks on said chain, whereby the distance between said blocks may be changed at will, said chain having a side wall, and each block being split to straddle said wall, said wall and said mechanism coöperating to hold the blocks against upward movement.
9. A machine for making wire-bound box blanks, comprising blocks for spacing the cleats of the blanks apart endwise, a chain, each block being split to straddle a part of the chain, and cams for adjustably securing the blocks to said chain, said cams having vertical axes.
10. A machine for making wire-bound box blanks, comprising blocks for spacing the cleats of the blanks apart endwise, a chain, each block being split to straddle a part of the chain, and cams for adjustably securing the blocks to said chain, said cams being disposed along the inner side of said chain.

Signed by me at St. Louis, Missouri, this
8th day of September, 1911.

HOWARD G. MEAD.
